SAFETY APPARATUS FOR SUBMARINES

Leo Y. Booharin, San Francisco, Calif.

Application October 7, 1939, Serial No. 298,462

12 Claims. (Cl. 114—16.5)

This invention relates to safety apparatus for submarines, and has for one of its objects the provision of means on a submarine for insuring an adequate supply of atmospheric air to the occupants of the submarine in the event the latter is disabled while submerged, and to exhaust the foul or stale air or gas from the submarine.

Another object of the invention is the provision of releasable signal means carried by a submarine and permanently attached thereto for enabling the occupants of a submerged submarine to communicate directly with persons above the surface of the water either audibly or visually, or both, and which signal means also will function to visually indicate the location of the submarine.

Another object of the invention is the provision of means for supplying an adequate amount of atmospheric air to a disabled submarine to enable working of pumps for exhausting water from the submerging tanks for increasing the buoyancy of the submarine, and at the same time supply atmospheric air to the occupants of the submarine and to discharge foul air or gas from the submarine.

A still further object is the provision of improved power actuated means for raising the bow or stern of a submerged submarine, as desired, or for simultaneously raising the bow and stern.

Other objects and advantages will appear in the specification and drawings annexed hereto.

In the drawings, Fig. 1 is a diagrammatic view of a submarine showing my invention.

Fig. 2 is a sectional view taken through one of the elements of the invention.

Fig. 3 is a part sectional and part elevational view of a housing on the deck of a submarine enclosing the device shown in Fig. 2 and the length of air line and some of the other features of the invention.

Fig. 4 is a fragmentary bottom plan view of one of the elements of the invention as seen from line 4—4 of Fig. 3.

Fig. 5 is a sectional view taken along line 5—5 of Fig. 2.

In detail, referring to Fig. 1, the upper deck 1 of the submarine is formed with a forward recess 2 adjacent the bow, and a rear recess 3 adjacent the stern. In recess 2 is a pair of horizontal propellers 4 having shafts 5 extending slidably through conventional stuffing boxes to below deck where they connect at their lower ends by conventional gears in boxes 6 with the ends of the drive shaft of motor 7, the power for the latter being supplied by storage batteries 8. A pair of threaded posts 9 at opposite sides of the motor support the motor by means of threaded blocks 10 rigidly secured to said opposite sides of the motor, and through which the posts pass with their threads engaging the threads of the

block. The posts 9 are rotatably supplied in suitable bearings at the opposite ends and a spiral gear is secured to the lower end of each shaft, which spiral gear meshes with a worm gear on horizontal shaft 11 that rotatably extends through partition 12 in the submarine, the outer end of the shaft being provided with a hand wheel 13 for turning the shaft.

The same construction is provided at the rear 10 of the submarine for the propeller in recess 3, and corresponding elements are similarly numbered, but are primed.

In operation, in the event raising of the bow is desired, the motor 7 is actuated, causing rotation 15 of the propellers 4 in the desired direction, and this action, together with manual turning of the hand wheels 13 will raise the motor and propellers 4, to the point where the latter are appreciably spaced above the level of the deck and 20 out of the recess 2. To withdraw the propellers into the recess, the hand wheels are actuated to lower the motor and propellers. The stern propellers 4' may be similarly actuated, for raising the stern, or both bow and stern propellers may 25 be actuated.

Adjacent the rear side of conning tower 14, I provide a cylindrical sided, vertically disposed container 15, and a similar container may be disposed adjacent the forward side of the conning 30 tower. In Fig. 1, both containers are indicated, and since both are identical in construction, only the rear container will be described in detail, but the same numbers will be used to identify corresponding elements associated with each.

Each of the containers 15 supports therein a 35 length of hose 16 say from 300 to 400 feet, more or less. This length of hose is in a coil, and in reality, comprises a pair of hose, or air lines, enclosed in a tubular sheathing, as will later be described more in detail. The respective air lines 40 in hose 16 at one end with a buoyant device 17, and at their opposite ends with separate pipes 18, 19 extending below the bottom of the container and into one of the compartments in the 45 submarine, as best indicated in Fig. 1. Said pipes are connected by a pipe 20 having a valve 21 therein, so as to form a communication between both of the air lines in hose 16, when desired. A manually actuated rotary air pump 22 is 50 at the outer end of pipe 19, and spaced well above the floor 23 of the submarine, while pipe 18 extends at its outer end to a point adjacent the floor where it connects with the lower end of a reciprocating exhaust pump 24 having check 55 valve 25 between the pump and end of pipe 18 for preventing suction of air from the pipe into said pump, while a check valve 26 at the opposite side of the lower end of pump 24 admits air at about the floor level to the pump for exhaustion 60 of the same into pipe 18. The rotary pump 22

upon actuation thereof draws air from pipe 19 for exhaustion into the compartment in which it is positioned.

Valve 21 is in the length of pipe 19 at a point between pump 22 and the point where the one end of pipe 20 connects therewith and a valve 21' is in the length of pipe 18 between the container 15 and the point where the opposite end of pipe 20 connects with pipe 18.

Container 15 has dome-shaped cover 28 bolted to the upper end of said container, and said cover is centrally apertured through an upwardly projecting neck 29, the inner sides of which neck are convex in curvature to provide rounded sides.

Centrally positioned within said neck, and spaced from the sides thereof, is the hollow, cylindrical, vertically extending buoyant device 17, which will hereafter be referred to as a buoy.

The sides and lower end of said buoy are integral, while the upper end is closed by a hemispherical cover 30 secured against the upper edges of the straight sides of the buoy by bolts 31. This cover is formed with a conduit 32 depending therefrom, which conduit is longitudinally divided by a central partition 33 (Fig. 2), thus providing an air line 18' at one side of the partition and an air line 19' at the opposite side. The conduit walls including the partition, extend through the cover 30, and above said cover, it divides to form separate necks 38, 39 extending oppositely outwardly of partition 33. The partition itself extends upwardly and outwardly past the upper sides of the necks, as at 40, and the outer edge of said partition where it extends outwardly of the conduit, is hemispherical in longitudinal contour (Fig. 5), as indicated at 41. This edge of the partition fits within a hemispherical groove 42 extending longitudinally in a hemispherical ridge 43 that projects inwardly within a dome-shaped cap 44 that encloses the cover 30 of the buoy. Ears 45 on said cap are secured by bolts 46 to said cover 30. The portion of the partition connecting with said cap thus serves to form a partition in the latter dividing the same into a chamber 47 into which the mouth of neck 39 opens. The walls of chamber 47 and 48, respectively, are provided with vent openings 49 just above the junction between the cap and cover 30, for discharge of air or gas from the chambers respectively.

In each of the chambers 47, 48, and at a level between the mouths of necks 38, 39 and openings 49, the said cover 30 is formed with a slightly downwardly inclined lip 50 for drawing any water that may enter said chambers to said openings. The outer edges of said lips are spaced from the inner sides of cap 44, thus permitting this drainage to the openings, and said lips overhang a portion of cover 30 therebelow to form a groove 51 extending circumferentially and horizontally around the cover 30, thus causing the lips to act as baffles to deflect water splashing in through openings 49 from passing into the main portion of chambers 47, 48 into which the mouths of necks 38, 39 open.

The conduit 32, partitions 33, 40, necks 38, 39 and lips 50 are all formed integrally with cover 30, and over each of the open mouths of necks 38, 39 is secured a cap 52, each of said caps carrying a sealing disk or washer therein that seals against the edges of said mouths. Each neck is formed with an outwardly projecting flange around the mouth thereof, and the sides of the caps are of spring metal split transversely,

as indicated in Fig. 1, so as to be yieldably held sealed against said mouths, but removable under internal air pressure.

The length of conduit 32 extending into the buoy 17 is split at its lower end to form separate, spaced extensions 53, 54 of the conduit, the extension 53 being in extension of line 18' and extension 54 being in extension of line 19'. These extensions are connected at a point intermediate their ends by a horizontal seating block 55 adapted to seat against the flat upper surface of inner side of lower end 56 of the buoy. The ends of extensions 53, 54 below block 55 extend through apertures 57, 58 of the lower end of the buoy when said block is seated against said lower end, suitable packing being provided to form water proof joints at said apertures. The lowermost ends of said extensions 53, 54, project through said lower end 56 and outwardly thereof, and are externally threaded for packing nuts 59, which nuts carry externally, coarsely threaded or grooved nipples for connecting with hose 18a and 19a that are enclosed within the large hose 16. Hose 18a thus connects between pipe 18 and air line 18' in conduit 32, while hose 19a connects between pipe 19 and air line 19' in the conduit.

The main hose 16 that encloses hose 18a, 19a, is flared at its end 16' adjacent the buoy 17 to extend over both of the nuts 59, and is secured rigidly to said buoy between flange 61 of a ring threaded to a boss formed on the outer side of said lower end 56 of said buoy.

The opposite end portion of the hose 16 is formed with an outwardly projecting reinforced flange 62 that is clamped between the margin of an aperture centrally positioned in the bottom container 15, by a flanged ring 63, and the hose 18a, 19a extend outwardly of the bottom of container 15 into the submarine, where they connect at 64 with pipes 18, 19 respectively.

Within the buoy 17 and supported near the bottom thereof between an inwardly projecting flange 65 formed integrally with said buoy, and a clamping ring 66, are a plurality of dry batteries 67, which batteries are preferably segmentally formed to fit around the conduit 32 and their lateral inner sides and to follow the contour of the outer walls of the buoy at their opposite lateral sides. One conductor 68 extends from one terminal of a battery to one of the terminals of bulb 69 adjacent the upper end of a buoy, which bulb is carried in a reflector 70 behind a glass lens 71 secured in an opening in one of the sides of the buoy. Conductors 72, 73 extend respectively from the other terminal of the bulb and battery into air line 19' in conduit 32 and from thence through the hose 19a into pipe 19 where the opposite ends of said conduits extend outwardly of the pipe 19 at a point within the submarine for connection with a switch 74.

A conductor 75 extends from one of the terminals of another battery 67 to one terminal of a socket connector plug 76 secured in a side of the buoy near the upper end of the latter. Conductors 77, 78 extend from the other terminal of the socket plug 76 and the battery 67, to within air line 18' in conduit 32, and from thence through hose 18a and pipe 18 into the submarine 70 where they pass through a plug in the side of pipe 18 to connect with a telephone 79. The connector plug 76 is a conventional plug for plugging in a telephone for communicating with an occupant within the submarine, and the socket openings are exteriorly sealed by wax 80 or

other removable, water-proof coating, which coating is removed to permit plugging in a telephone.

The hose lines 18a, 19a, respectively, enclose a coil of spring wire 81 therein throughout their length, to prevent collapse of the hose under external pressure, and to prevent kinking of the hose. Also, said wire tends to hold the coils of hose in the container 15 against the outer walls against accidental shifting therein.

The buoy 17 is releasably held in container 15 by a centrally divided dome-shaped cap 82. The halves of said cap, respectively, are pivoted at 83 to opposite outer sides of the neck 29 of the container to permit swinging the halves together and also apart. Around the lower edge of the cap 82 is an inwardly projecting flange 84 (Fig. 2), which flange is formed with a laterally opening V-shaped groove 85 adapted to receive therein an outwardly projecting flange 86 formed around the upper end of the buoy, the cross sectional contour of said flange being complementary to the V-shaped groove 85. Thus when the weight of the buoy, when the flange 86 is in groove 85, will hold the buoy centrally within the upper end of the container, and the walls of the cap 82 will cover the buoy. The tighter the buoy is drawn downwardly the tighter the cap will grip the buoy. To hold the buoy tightly within the cap, I form eyes 87 at opposite sides of the lower end of the buoy, and wires 88 extend through packing nuts 89 in the bottom of the container to within the submarine, where the lowermost ends, respectively, pass through openings in brackets 90 and through a similar opening in a shear arm 91 pivotally secured at 92 (Fig. 4) to the under side of each bracket. The ends of wires 88 projecting below the arms are each secured to a pin 93, thus securely holding the wires taut, and preventing accidental escape of the buoy.

The container 15 is not water-tight, hence when the submarine is submerged, the buoyancy of the buoys tend to rise, but are held against so doing by the wires 88, which wires likewise hold the cap 82 closed.

In operation, in the event of submersion of a submarine, and its inability to rise to the surface, the operator merely strikes the shear arms 91 to pivot on pivots 92, whereupon the wires are released, and the buoyancy of the buoy carries the latter upwardly to the surface, dragging the hose 16 with it. The packing glands or nuts 89 are preferably self-sealing after the wires 88 have been carried therethrough, but in any event the openings are readily and easily sealed shut by forcing the packing across the openings.

Immediately upon the buoy reaching the surface, the light bulb 69 may be actuated by switch 74 to signal for help or to give information as to the location of the submerged craft.

After the buoy has reached the surface of the water, assuming valves 21, 27, 27' are closed, the operator opens valves 21, 27 and pump 24 is actuated to create sufficient pressure to blow off caps 52 on the necks 38, 39 that are in the uppermost end of the buoy. If either one of the caps blows off before the other, by obvious manipulation of valves 21, 27', the other cap will be blown off, thus opening the air lines 18', 18a and 19', 19a to through communication between the atmosphere and the pipes 18, 19 within the submarine. Upon closing valve 21 and opening both valves 27, 27' the actuation of both of the pumps 22, 24 will result in exhausting foul heavy air or

gas from the submarine while fresh atmospheric air will be brought into the latter.

The admission of a fresh and continuous air supply of air to within the submarine will enable the occupants of the latter to actuate pump 94 (Fig. 1) for pumping air into the ballast or descending tanks 95 formed by the double bottom of the submarine for exhaustion of said water through the conventional check valve 97.

10. The pair of buoys and hose lines, etc., are provided to permit any of several rooms in the submarine to receive fresh air in the event it is found expedient to close the doors for any reason.

It is obvious, of course, that the buoy 17 may be spherical, or of any other desired shape, and the relative proportions of the buoy and other elements may be modified to suit particular conditions.

Having described my invention, I claim:

1. A safety device for submarines including a hollow, water-tight buoy provided with a pair of conduits extending therethrough and outwardly of the buoy at opposite sides thereof, one of the ends of said conduits being formed for connection with a pair of flexible air hose, closures frictionally and removably secured over the opposite ends of said conduits, a cap secured over said opposite ends and spaced therefrom for forming a chamber enclosing said opposite ends, a partition extending between said cap and buoy and disposed between the said opposite ends for dividing the said chamber into two compartments with one end of each conduit in each compartment, and said cap being formed with an opening into each compartment providing air communication between the atmosphere and each compartment.

2. In a construction as defined in claim 1, the openings in said cap being disposed adjacent the buoy and means removably securing said cap to said buoy.

3. A safety device for submarines including a hollow water-tight buoy, an open ended conduit for air extending through said buoy with its opposite ends opening outwardly of opposite sides of said buoy, means for connecting one end of said conduit with a flexible air hose, closure means removably secured over the opposite end of said conduit closing the opening in said opposite end, an electrical battery secured within said buoy adjacent said one end of the conduit, electrically actuated signalling means carried by said buoy electrically connected with said battery for actuation thereof and actuating means for causing actuation of said signalling means by said battery from a point within a submarine remote from said buoy, means removably securing said battery in said buoy against displacement in any direction relative to the walls of said buoy.

4. In a construction as defined in claim 3, a flexible air hose connected at one end with said one end of the conduit, means connecting the opposite end of said hose with a submarine, said actuating means including electrical conductors extending through said hose and into said submarine, and means actuatable from within said submarine for causing removal of said closure means and for drawing air through said conduit and hose into said submarine.

5. A safety device for submarines comprising a normally vertically disposed, hollow, water-tight buoy having walls defining a chamber outwardly of its upper end separated by the upper wall of said buoy from the interior of said buoy,

and said buoy being formed to normally flat in water with said chamber above the water level; a vertical partition dividing said chamber into two separate compartments; a pair of vertical, open ended conduits extending through said buoy and outwardly of the upper and lower sides thereof, respectively connected at their lower ends with hose lines at their lower ends for communicating with the interior of a submerged submarine when the buoy is floating on the surface of the water; the upper ends of said conduits each opening into one of said compartments; the outer walls of said chamber above said buoy being formed with a pair of ports respectively opening into each of said compartments for separately porting said compartments to the atmosphere; and a baffle in each compartment between each of said ports and each of the upper open ends of said conduits for deflecting water that may enter said ports from said upper open ends.

6. In a construction as defined in claim 5, said buoy being generally cylindrical and vertically elongated, the said walls of said chamber being in the form of a generally hemispherical cap with its concave side facing downwardly, and means securing the said cap at the edges to the upper end of said buoy.

7. In a construction as defined in claim 5, the baffle in each of said compartments being formed in the upper wall of said buoy, and extending generally horizontally outwardly relative to said partition, and said upper one ends of said conduits being positioned above said ports and above said baffles and said baffles being positioned above said ports.

8. In a construction as defined in claim 5, the upper wall of said buoy extending slantingly downwardly away from opposite sides of said partition for drawing water away from said partition and the baffle in each compartment being carried by and substantially coplanar with the portion of said upper wall in each compartment so extending from said partition and terminating in free edges adjacent the inner sides of the lateral outer walls of said chamber, but slightly spaced from said inner sides; said ports being disposed below said free edges, and said upper end portions of said conduits being curved in direction away from each other with said open ends facing away from said partition.

9. A safety device for submarines comprising a hollow, water-tight buoy having walls defining a chamber outwardly of its upper end separated by the upper wall of said buoy from the interior of said buoy, a pair of open-ended, vertical conduits extending through said buoy and into said chamber, a pair of caps respectively frictionally secured over the ends of the conduits that project into said chamber, each of said caps being arranged and adapted to be held tightly against the end of the conduit to which it is attached by pressure of water when the buoy is submerged and to be blown off said conduit by air within the conduit at greater than normal atmospheric pressure; a vertical rib carried by the upper wall of said buoy connecting with the upper wall of said chamber outwardly of said upper wall of the buoy dividing said chamber into two compartments into each of which one of the upper ends of said conduit extends, and means removably

securing the upper and lateral walls of said chamber to said buoy, said lateral walls being formed with ports opening outwardly of said chamber at points positioned a substantial distance below the upper open ends of said conduits and the remainder of said walls being imperforate, and means between said ports and said open upper ends arranged and adapted to deflect water that may be splashed through said ports

10 in a direction away from said open upper ends to prevent such water from entering said open ends.

11. In a submarine, a safety device comprising a buoy provided with a pair of vertical conduits 15 for air therethrough projecting outwardly of the upper end of said buoy when the latter is floating in water; a pair of extensible hose lines connected with the lower ends of said conduits and extending into said submarine; a relatively flexible, 20 severable wire secured to said buoy and slidably extending through one of the walls of said submarine into the latter, means securing the said wire to said submarine at a point within the latter, and means for severing said wire adjacent 25 said point and between said point and said buoy for releasing the buoy for floating to the surface of water.

12. In a construction as defined in claim 10, 30 housing between said buoy and said one of the walls of said submarine enclosing said hose lines, said housing having a pair of doors hinged thereon swingable toward each other and toward said buoy to grip said buoy at opposite sides thereof, and means comprising said wire, arranged and 35 adapted to hold said doors in gripping relation to said buoy, said doors being automatically responsive for movement to open position releasing said buoy by upward movement of said buoy when said wire is severed.

13. In a submarine, a safety device comprising a vertically disposed, cylindrical buoy provided with a pair of vertical conduits for air extending therethrough and projecting therefrom at their upper and lower ends; a pair of hose lines connected between said submarine and said lower ends of said conduits; buoy securing means on 45 said buoy extending into said submarine securing said buoy to said submarine adjacent the upper wall of the latter; a housing enclosing said hose lines having a pair of doors at opposite sides of said buoy when the latter is secured to said submarine by said buoy securing means and having adjacent edges engaging opposite sides of said buoy; means mounting said doors for swinging 50 of said adjacent edge apart to release said buoy, means including said buoy and said buoy securing means holding said doors in position with said edges engaging opposite sides of said buoy; means for releasing said buoy supporting means from 55 securement to said submarine, and said doors being arranged and adapted to automatically swing apart and away from the buoy under the influence of upward movement of the said buoy when the said buoy is released from securement 60 to said submarine, said doors being recessed along said adjacent edges to conform to the cylindrical 65 contour of said buoy and to embrace said buoy and to provide an opening for said hose lines to follow said buoy when the latter is released from said submarine.
